HOLDER FOR PESTICIDES AND THE LIKE

Harold A. Lutes, 5128 Corolite St.,
Long Beach, Calif. 90808

Filed Nov. 17, 1972, Ser. No. 307,427

Term of patent 14 years

Int. Cl. D22—06

U.S. Cl. D22—18

FIG. 1 is a perspective view of a holder for pesticides and the like shown in my new design;

FIG. 2 is a front view of the holder shown in FIG. 1;

FIG. 3 is a left hand end view of the holder shown in FIG. 1;

FIG. 4 is a back view of the holder shown in FIG. 1;

FIG. 5 is a right hand end view of the pesticide holder shown in FIG. 1;

FIG. 6 is a top view of the pesticide holder shown in FIG. 1; and

FIG. 7 is a bottom view of the pesticide holder shown in FIG. 1.

I claim:

The ornamental design for a holder for pesticides and the like, substantially as shown.
